(57) **CLAIM**

The ornamental design for a vehicle grille, as shown and described.

DESCRIPTION

FIG. 1 is a top front isometric view of a vehicle grille according to our new design;

FIG. 2 is a front view of the vehicle grille of FIG. 1;

FIG. 3 is a rear view of the vehicle grille of FIG. 1;

FIG. 4 is a top view of the vehicle grille of FIG. 1;

FIG. 5 is a bottom view of the vehicle grille of FIG. 1;

FIG. 6 is a left side view of the vehicle grille of FIG. 1;

FIG. 7 is a right side view of the vehicle grille of FIG. 1;

FIG. 8 is a cross-sectional view taken along line 8-8 in FIG. 2;

FIG. 9 is a top rear isometric view of the vehicle grille of FIG. 1; and,

FIG. 10 is a partial enlarged view of the vehicle grille of FIG. 1.

The broken lines show portions of the vehicle grille which form no part of the claimed design.

1 Claim, 8 Drawing Sheets
